DESIGN FOR A WASHING MACHINE

Henry W. Altorfer, Peoria, Ill.

Application November 17, 1938, Serial No. 81,171

Term of patent 14 years

To all whom it may concern:

Be it known that I, Henry W. Altorfer, a citizen of the United States and a resident of Peoria, in the county of Peoria and State of Illinois, have invented a new, original, and ornamental Design for a Washing Machine, of which the following is a specification, reference being had to the accompanying drawing, forming part thereof,

The figure is a perspective view of a washing machine, showing my new design. The other sides are substantially like the sides shown.

I claim:

The ornamental design for a washing machine, as shown and described.

HENRY W. ALTORFER.
